UNITED STATES PATENT OFFICE.

GEORGE A. TANNEY, OF CHICAGO, ILLINOIS.

GAME MECHANISM.

1,243,642.

Specification of Letters Patent. Patented Oct. 16, 1917.

Application filed October 27, 1916, Serial No. 128,052. Renewed September 17, 1917. Serial No. 191,897.

To all whom it may concern:

Be it known that I, GEORGE A. TANNEY, a citizen of the United States, and a resident of Chicago, in the county of Cook and State 5 of Illinois, have invented certain new and useful Improvements in a Game Mechanism, of which the following is a specification.

This invention relates to mechanism whereby a game may be played by children, 10 and by said game they will be educated in addition, subtraction, division and multiplication.

The object of the invention is to obtain mechanism adapted to be used in playing 15 games by adults and children; and by the playing said games the parties engaged therein will become adepts in mental arithmetic.

I have illustrated the invention by the 20 drawing accompanying and forming a part hereof, in which—

Figure 1 is a top plan view;

Fig. 2 a vertical section, and

Fig. 3 a horizontal section of the device 25 embodying the invention.

Broken lines 2—2, and 3—3, of Figs. 1 and 2, indicate the lines of said sections, and the arrows on said lines indicate the direction in which the said sections are 30 viewed.

A reference character applied to designate a given part indicates said part throughout the several figures of the drawing, wherever the same appears.

35 X is the base of the device, and comprises the inclined upper face a, having the central point B, the ripples b, and the pockets C. Pockets C are illustrated as obtained by the radially extending raised ribs E. D are 40 marks designating certain pockets, and indicate that division of a determined sum is to be made. A, S, and M, respectively, are 45 marks designating certain pockets, and indicate that addition, subtraction and multiplication of determined numbers or sums are 50 to be made, when the ball (F) is lodged in the pockets indicated by said marks. G are numerals in certain pockets, and respectively indicate that the numeral in a given 55 pocket is a factor in the game played by means of the device. g is a rim or boundary wall to base X. H are apertures in base X, which are substantially equi-distant from the central point B.

55 I is a tower comprising the standards J, fitting at their lower ends in apertures H,

and partitions K, L, and N. Partitions K, L, and N, are respectively provided with apertures k, l, and n. The upper faces of the partitions K, L, and N flare upwardly 60 and outwardly, as at k', l' and n'. P, p, are wires which are secured in the partitions K and L, to extend a short distance below the under surface of said partitions, and to cross each other at substantially right angles. Q is a removable shell or casing to the tower I.

To play a game with this device the ball F is permitted to fall or pass downwardly to the aperture k in partition K. The 70 passage way (R) through said tower I is interrupted by the crossed wires P, p, and the partitions L and N; so that the travel of said ball through said passage-way, is not directed by the manner in 75 which said ball is deposited in the aperture k; but said ball is eventually discharged from aperture n on to the upper face of base X, and from thence it moves down the inclined face a, over ripples b, and into some 80 one of the pockets C.

By previously determined rules certain values are given to the pockets which are designated by numerals; and said values are applied when the ball becomes lodged 85 in said pockets. When the ball lodges in a pocket which is designated by the letter A, D, S, or M, an arithmetical problem is presented to the party who has played the ball 90 so lodged; said problem being to add, divide, subtract or multiply by a factor determined by said rules the sum or value attained or about to be attained by plays of said player.

When a game is played by a child, or 95 children, the problems presented tend to exercise said child or children in what is termed mental arithmetic, under the guise of play.

I claim;—

1. In a game mechanism, a base the upper 100 face whereof inclines downwardly from a central point, said base being provided with pockets at the lower end of said inclined face and with ripples between said central point and said pockets, in combination with 105 a tower which is provided with an interrupted passage way and is mountable over said central point, and a ball which is adapted to travel through said passage way and over said rippled surface to said pockets. 110

2. In a game mechanism, a base the upper 115 face whereof inclines downwardly from a

central point and is provided with pockets at the termination of said inclined face, means to identify said pockets, said means including marks indicating addition, subtraction, division and multiplication, in combination with a tower over said central point, said tower provided with an interrupted passage way therethrough, and a ball adapted to travel through said passage way 10 and over said inclined face to said pockets.

3. In a game mechanism, a base the upper face whereof inclines downwardly from a central point and is provided with pockets at the termination of said inclined face, 15 means to identify said pockets, said means including marks indicating arithmetical operations, means to interrupt direct travel of a ball from said central point to said pockets, in combination with a tower which is provided with an interrupted passage way, and 20

a ball adapted to travel through said passage way and over the upper face of said base to said pockets.

4. In a game mechanism, a base provided on the upper face thereof with pockets and 25 with an inclined face extending from said pockets upwardly to a central point, means to indicate said pockets, said means comprising marks indicating arithmetical operations, and a ball adapted to travel from 30 said central point into said pockets, in combination with a tower mountable over said central point, said tower provided with a passage way therethrough and said ball adapted to travel through said passage way. 35

GEORGE A. TANNEY.
